Atty.*

UNITED STATES PATENT OFFICE.

FRANK H. BURDSALL, OF CAMDEN, NEW JERSEY.

DESIGN FOR A STUB-PEN.

SPECIFICATION forming part of Design No. 32,730, dated May 29, 1900.

Application filed May 1, 1900. Serial No. 15,145. Term of patent 14 years.

To all whom it may concern:

Be it known that I, FRANK H. BURDSALL, a citizen of the United States, residing at Camden, in the county of Camden and State of New Jersey, have invented and produced a new and original Design for Stub-Pens, whereof the following is a specification, reference being had to the accompanying drawings.

Figure 1 is a plan view of a stub-pen, showing my new design; and Fig. 2 is a side view of said pen.

The pen shown in the drawings comprises three parts—the bowl A, the shell B, and the heel C, and it is to be observed that the bowl A is of greater breadth than the heel C and that the shell B is of less breadth than said heel C.

The leading or material feature of my design consists in the peculiar configuration of the bowl A, comprising the abruptly-divergent

concave curved point edges a and concave curved side edges a', which join in outwardly-flared corners at a², substantially in line with the pierce-hole a³. As shown, the side edges a' of the bowl are abruptly recurved at a⁴ at 25 their junction with the side edges b of the shell B, and curved recesses c are formed in the side edges c' of the heel C, immediately adjoining said shell B, said edges c' being substantially straight and parallel and connected 30 by the convexly-curved rear edge c².

Having described my invention, what I claim as new, and desire to secure by Letters Patent, is—

The design for a stub-pen as herein shown 35 and described.

FRANK H. BURDSALL.
